CLEANING AND ANNEALING TANK FOR
DENTAL INLAYS, CASTINGS, AND THE
LIKE

Burton Spier, New York, N. Y.

Application August 24, 1950, Serial No. 181,202

3 Claims. (Cl. 134—143)

1

The present invention relates to a tank or receptacle for use in cleaning and annealing gold or other precious metals, and more particularly to a type of tank or receptacle that may be used advantageously and effectively in a dental or chemical laboratory for cleaning and annealing gold inlays, castings and the like.

In the practice of dentistry, after a gold or other precious metal inlay or casting has been prepared, and prior to setting it permanently and securing it within the patient's mouth, the usual procedure is to heat the inlay or casting in order to make it more malleable and to treat the inlay or casting with an acid that will remove and dissolve any foreign matter that may have adhered thereto. This is generally accomplished by holding the inlay or casting with a suitable instrument in the flame of a Bunsen burner until a required degree of heat is attained, then dropping the inlay or casting into a receptacle containing hydrochloric or nitric acid, and after the inlay or casting has been annealed and cleaned of all foreign matter by the acid, it is withdrawn from the receptacle. It is common knowledge that in the course of the said process, the contact of the heated inlay or casting with the acid will cause noxious acid fumes to be generated, which when emitted into the atmosphere are not only injurious to the health of persons who may breathe the fumes, but are also damaging to metal fittings, fixtures, tools, instruments and other metal objects that may come in contact therewith. Normally the acid receptacle is kept tightly covered, but the insertion therein and the removal therefrom of the inlay or casting permits the fumes to escape into the atmosphere. To overcome this condition and to prevent the damaging results therefrom I have provided an acid tank or receptacle of improved and novel design and construction which I believe to be a practical solution to the acid fumes problem.

The principal object of the present invention is, therefore, to provide an acid tank or receptacle for use in cleaning and annealing gold inlays and castings and the like, which is designed to prevent acid fumes formed therein from escaping into the atmosphere. Another object of the invention is to provide a tank or receptacle of the character described and for the purposes mentioned, which is portable and convenient to handle, and is adapted to be used effectively in a dental or chemical laboratory. A further object of the invention is to provide a tank or receptacle of the aforesaid type and design, which is simple in construction and economical to

2

manufacture. Other objects and advantages of the present invention will in part be pointed out hereinafter and will otherwise be apparent to those skilled in the art to which the present invention relates.

With the above and other objects in view my invention comprises the novel features of construction and arrangement of parts hereinafter described and illustrated in the accompanying drawing, wherein the preferred physical embodiment of my invention is shown.

In the accompanying drawing which forms an integral part of this specification,

Fig. 1 is a top plan view, partly in section taken along the line 1—1 of Fig. 2, of an acid tank or receptacle designed and constructed in accordance with the present invention.

Fig. 2 is a side sectional elevation thereof taken on the line 2—2 of Fig. 1; and

Fig. 3 is a fragmentary perspective view of the tray member of the tank or receptacle.

Referring now in detail to the drawing wherein like reference characters indicate corresponding parts throughout the several views, there is shown a tank or receptacle constructed in accordance with the present invention, the tank or receptacle being made preferably of a suitable heat and acid resisting transparent material such as the type of glass known as "plexiglas," but other materials such as metal and porcelain may equally serve the purpose. The tank or receptacle is preferably rectangular in shape and comprises a bottom 10, side walls 11 and 12, end walls 13 and 14 and a top 15. The top of the tank is provided with openings 16 and 17 therein, and fitted snugly within the openings 16 and 17 are the covers 18 and 19 respectively. Each of the covers 18 and 19 is provided with a knob or handle 20, 21, which may be conveniently gripped with the fingers for removing the cover from and replacing it within its respective opening. The end walls 13 and 14 of the tank are preferably provided with handles 22 and 23 respectively which may be conveniently gripped for transporting the tank from place to place.

The interior of the tank is provided with a diagonally disposed partition forming an inclined platform 24 which extends transversely from the side wall 11 to the side wall 12 and slopes downwardly from the end wall 13 to the bottom 10 of the tank. For reasons hereinafter set forth the slope of the platform 24 is of such degree that an object placed thereon will normally gravitate to the bottom of the incline. Also provided within the interior of the tank is

another partition 25, substantially parallel with the partition 24, and extending between the openings 16 and 17 in the top of the tank. The interior of the tank is thus partitioned to provide a liquid containing compartment extending between the partitions 24 and 25.

The tank is further provided with a vertically disposed partition 26 which extends longitudinally from the side wall 11 to the side wall 12, and is movable through a slot 27 in the top of the tank and through a slot 28 in the partition 25. The upper edge of the moveable partition 26 is preferably provided with a head 29 which projects above the top of tank and may be conveniently gripped for raising and lowering the partition, and the lower edge of the partition 26 normally rests on the inclined platform 24. The sides of the partition 26 are preferably wedge shaped so as to frictionally engage the walls of the slots 27 and 28 and to form a tight fit therein. It will be readily observed that the partition 26 serves to divide the liquid containing compartment of the tank into two inter-communicating compartments A and B.

The cover 19 is provided with a depending member 30 which is connected to a U-shaped tray 31. When the cover 19 is in closed position within the opening 17 the tray 31 normally rests on the bottom of the tank adjacent to the lower end of the inclined platform 24. The bottom of the tray 31 is preferably provided with perforations 32 to permit the liquid in the tank to drain therethrough when the cover 19 is lifted from and replaced within the opening 17, thereby facilitating the raising and lowering of the tray 31 within the tank.

Contained within the compartments A and B is an acid 33, such as hydrochloric or nitric acid, which is suitable for cleaning and annealing gold or other precious metal inlays or castings. Sufficient acid is generally contained within the tank to prevent the flow of air or gases from compartment A to compartment B when the partition 26 is raised.

In using the tank of the present invention for cleaning and annealing an inlay or casting, the cover 18 is lifted from the opening 16 in the top of the tank, and the inlay or casting, which had just previously been heated to a required degree of heat by holding it in the flame of a Bunsen burner, is dropped into the acid in compartment A, and the cover 18 is immediately replaced over the opening 16. The inlay or casting will then fall onto the platform 24 and will slide down the incline, but will be retained within the compartment A by the partition 26. The contact of the inlay or casting with the acid will cause acid fumes to be generated within compartment A and these will accumulate in the air space in compartment A above the acid 33. After the inlay or casting has been submerged in the acid for an interval and has been cleaned and annealed by the acid, the partition 26 is then raised by an upward pull on the head 29, and the inlay or casting is thus permitted to slide down the platform 24 into the compartment B and to fall into the tray 31 resting in the bottom of the tank. The cover 19 is then lifted from the opening 17 in the top of the tank and the tray 31 which is connected to the cover 19 is brought to the top of the tank to permit the inlay or casting to be removed therefrom.

It will be observed that when the partition 26 is raised, the acid fumes which have accumulated in the air space above the acid 33 in com-

partment A, are prevented by the acid from passing into the air space above the acid 33 in compartment B. The acid fumes generated in the tank are thus prevented from escaping into the atmosphere when the cover 19 is lifted to remove the inlay or casting from the tray 31. It has been found that after a lapse of time the acid fumes in compartment A are absorbed by the acid. Therefore, since the process is performed at substantial intervals, the acid fumes which have been formed in compartment A will generally have been completely absorbed by the acid before it becomes necessary to repeat the process, and there will be no fumes remaining in compartment A to escape into the atmosphere when the cover 18 is again lifted from the opening 16.

It is evident from the foregoing description and illustration that my improved acid tank is simple and practical and may be used to great advantage in a dental or chemical laboratory, for cleaning and annealing gold and other precious metal inlays, castings and the like. I desire it to be understood, however, that the present invention is not limited to the specific embodiment thereof herein described and illustrated in the drawing, but that variations in the details of construction are contemplated, which will nevertheless come within the scope of my invention as set forth in the appended claims.

Having thus described and illustrated my invention, what I claim as new and desire to secure by Letters Patent is:

1. An acid tank for use in cleaning and annealing dental inlays, castings and the like, comprising a substantially rectangular shaped receptacle including a bottom, side walls, and a top having openings towards opposite ends thereof, removable covers for said openings, a tray normally resting on the bottom of the tank below one of said openings and connected to the cover for said opening, an inclined platform extending transversely between the top and bottom of the tank and sloping toward said tray, and a vertically disposed partition extending across the tank between said openings and adjoining opposite side walls thereof, said vertically disposed partition normally resting on said inclined platform and being moveable upwardly through a slot in the top of the tank, substantially as described.

2. An acid tank for use in cleaning and annealing dental inlays, castings and the like, comprising a substantially rectangular shaped receptacle including a bottom, side walls, and a top having openings towards opposite ends thereof, removable covers for said openings, a tray normally resting on the bottom of the tank below one of said openings and connected to the cover for said opening, an inclined platform extending transversely between the top and bottom of the tank and sloping toward said tray, a diagonally disposed partition below the top of the tank, substantially parallel with said inclined platform and extending across the tank between the openings in the top of the tank and adjoining opposite side walls thereof, and a vertically disposed partition extending across the tank between said openings and adjoining opposite side walls thereof, said vertically disposed partition normally resting on said inclined platform and being moveable upwardly through a slot in the top of the tank and a slot in said diagonally disposed partition below the top of the tank, substantially as described.

3. An acid tank for use in cleaning and annealing dental inlays, castings and the like, comprising a substantially rectangular shaped receptacle, including a bottom, side walls, and a top having openings towards opposite ends thereof, 5 removable covers for said openings, a tray having perforations in the bottom thereof normally seated in the bottom of the tank below one of said openings and connected to the cover for said opening, an inclined platform extending 10 transversely between the top and bottom of the tank and sloping toward said tray, a vertically

moveable partition extending across the tank between said openings and adjoining opposite side walls thereof, the upper edge of said vertically movable partition projecting through a slot in the top of the tank and the lower edge thereof normally resting on said inclined platform, a supply of acid contained within the tank, and gripping means on the sides of the tank for transporting the tank, substantially as described.
